FIG. 5.

EDWIN B. HUGHSON

INVENTOR

BY *Victor J. Evans*

ATTORNEY

WITNESS:
A. Mank

UNITED STATES PATENT OFFICE

EDWIN B. HUGHESON, OF BIG INDIAN, NEW YORK

FUSE

Application filed April 29, 1931. Serial No. 533,771.

This invention relates to fuses for electric circuits.

An object of the invention is the provision of a fuse comprising a plug and a fuse proper which is readily replaceable in the plug.

Another object is the provision of a fuse structure in which the fuse proper is in such relation to the plug that it will be held in tight contact with a socket when the plug is inserted in the socket without employing fastening means such as screws or solder to fasten the fuse to the plug.

Other objects will be appreciated by those skilled in the art upon reading the following specification.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therefrom as do not affect the spirit of the invention nor exceed the scope thereof as expressed in the appended claim.

In the drawing:

Fig. 1 is a side view of the fuse.

Fig. 2 is a section taken on line 2—2 of Fig. 1.

Fig. 3 is a bottom plan view.

Fig. 4 is a top plan view; and

Fig. 5 is a perspective view of the fuse proper before being placed in the plug.

Referring to the drawing for a more detailed description thereof, numeral 7 indicates a plug which is preferably of insulating material such for example as glass or porcelain. The plug is provided with a recess 8 and has exterior threads 9 and a boss or protuberance 10 on the exterior of an end wall 11. The plug is provided with a transverse aper-

ture 12 extending through the side wall of the plug from the threads to the recess 8. The plug is also provided with a sloping aperture or passageway 14 extending from the threads through the end wall 11 to the exterior of the end wall at a point adjacent the protuberance 10.

The fuse proper is shown in Fig. 5 and is designated by the numeral 15. The fuse 15 comprises a body portion 16 having notches 17 at its sides to provide a portion of reduced cross-sectional area. One end of the fuse has an enlarged round contact portion 18.

The fuse 15 is placed in the plug by pushing the end 19 of the fuse through the aperture or passageway 14 of the plug from the lower end thereof and then fitting the body portion to one or more of the threads 9 and passing the end 19 through the aperture 12 and bending it downwardly into contact with a boundary portion of the recess 8. The round contact portion 18 of the fuse may then be bent over onto the protuberance 10. That portion of the fuse which has a reduced cross-sectional area by reason of the notches 17 lies in the aperture or passageway 14 so that when the fuse blows at this reduced portion protection will be given by the body of the plug. No special fastening means such as screws or solder is needed to hold the fuse in the plug since the ends thereof are held by the latter. It will be readily appreciated that when the plug is screwed into a socket that portion of the fuse which lies on the threads of the plug will be tightly held between the plug and the socket. It will also be readily seen that the fuse may be readily replaced on account of the fact that no auxiliary fastening means are employed.

What is claimed as new is:

A fuse plug comprising an exteriorly threaded body for insertion in a fuse block and having a boss at one end disposed in the center of the latter, and a fuse having a disk portion disposable against said boss, the body

having a recess therethrough entirely closed except adjacent said boss and at a point intermediate the length of the threads, the fuse extending through said recess to have a portion thereof lying exteriorly against said threads, the body of the fuse above the point where the latter leaves the recess being formed with a perforation in its wall communicating with the interior of the body, and the extremity of the fuse passing through this perforation.

In testimony whereof I hereby affix my signature.

EDWIN B. HUGHSON.
